UNITED STATES PATENT OFFICE.

ALLEN I. BLANCHARD, OF CHICAGO, ILLINOIS, ASSIGNOR TO THE NATIONAL CASH REGISTER COMPANY, OF DAYTON, OHIO.

CASH-REGISTER.

SPECIFICATION forming part of Letters Patent No. 610,379, dated September 6, 1898.

Application filed June 8, 1896. Serial No. 594,715. (No model.)

To all whom it may concern:

Be it known that I, ALLEN I. BLANCHARD, residing at Chicago, in the county of Cook, State of Illinois, have invented a certain new and useful Improvement in Cash-Registers, of which the following is a description, reference being had to the accompanying drawings, forming part of this specification.

My invention relates particularly to the registering mechanism of such machines and comprises a series of graduated cams actuated by the keys to transmit their value to the totalizing-counter.

Another feature of my invention relates to the transfer devices employed to transmit an amount registered through the primary registering-wheel of the counter and from the "cents" to the "dollars" counter-wheels.

A third feature consists of an auxiliary keyboard arranged to establish an operative relation between the five-cent-key cam and all the other keys representing odd multiples of that amount.

A fourth feature consists of a series of detail-adding wheels arranged to register the amounts in detail independently of the totalizing-counter above referred to.

The novel constructions and combinations will be more fully described, and pointed out particularly in the appended claims.

Referring to the accompanying drawings, forming part of this application, Figure 1 is a front elevation of the machine without the cabinet and the cash-drawer, which are omitted from all the drawings, as they are not essential to the operation of my invention. Fig. 2 is a vertical cross-section on the line 2 2 of Fig. 1. Fig. 3 is a similar view on the line 3 3 of Fig. 1. Fig. 4 is a bottom plan view showing particularly the auxiliary keyboard and the independent pivoted five-cent-key cam, which is arranged so as to be actuated either by the five-cent key or by the auxiliary keyboard. Fig. 5 is a view in perspective, showing the five-cent key and the five-cent-key cam pivoted coincidently therewith. Fig. 6 is a detail elevation view from the opposite side of the parts shown in Fig. 5. Fig. 7 is a detail view in perspective of the universal bar or keyboard, showing the stops for locking the registering mechanism upon the com-

pletion of the stroke of any operated key, also the standards carrying the plungers for turning the cam-wheel shown in Fig. 3. Fig. 8 is similar to Fig. 2, except that it shows in addition thereto one of the pairs of detail-adding wheels which are actuated by each of the keys.

Like figures of reference denote the same parts in all the figures of the drawings.

The side frames 10 11 are provided with bearings, in which is supported the main shaft 12, upon which the keys 13 are pivoted. At their rear ends the keys rest upon a horizontal cross-piece 14 of the frame. As usual in devices of this class, the indicators 15, upon which are numbers corresponding to the values of the respective keys, are carried by the indicator-rods 16, which rest upon the rear ends of the keys. Each indicator-rod is provided with a shoulder 17, adapted to engage or rest upon the wing 18, which is pivoted on the side frames, and by a co-operative action of the parts just mentioned the indicator of any operated key will be temporarily held in exposed position, but will be dropped out of sight upon the succeeding operation of any key in a manner now well known in the art.

Those keys of the machine shown in the drawings which represent numerical values are arranged in three banks or sets, the first banks comprising the nine keys representing from one cent to nine cents, inclusive, the second set the eighteen keys representing amounts from ten cents to nine-five cents, and the third set the nine keys representing amounts from one dollar to nine dollars, inclusive. Each bank comprises a series of graduated cams, one of which is secured to and, except in the case of the five-cent key, preferably formed integral with each key, according to the numerical value of the latter. Each series of cams co-operates with one of the three horizontally-pivoted swinging registering-boards, the cents bank with the board 19, the dimes bank with the board 20, and the dollar bank with the board 21, in a manner to be presently pointed out. These boards, which normally assume a vertical position, with their lower ends barely clearing the key-cams, are pivoted upon the stationary horizontal shaft 22, extending, in the pres-

ent instance, the entire width of the machine and journaled in brackets secured to the side frames 10 11, and coiled springs 23, each secured at the one end to the shaft 22 and at 5 the other to its adjacent registering-board, as shown in Fig. 1 of the drawings, serve to return the bars to normal position after they have been displaced. Actuated by the swinging registering-boards are the counter-driving gears 24, 25, and 26, also turning upon the horizontal shaft 22, and each of these gears is driven by its adjacent swinging registering-board through the medium of the driving-pawl arms 27, 28, and 29, which are fixed to 10 and movable each with its registering-board. Driving-pawls 30, 31, and 32 are pivoted to the pawl-arms and engage the counter-driving gears, respectively, so that any movement of the keys will be transmitted through the 15 key-cams to the swinging registering-boards, thence through the driving-pawl arms to the counter-driving gears, and finally through the pinions 33, 34, and 35, which are pivoted on the counter line-shaft to the counter-wheels 20 36, 37, 38, 39, 40, 41, and 42. The amount of movement so received by any of the counter-wheels is proportionate to the numerical value of the operated key, as shall be presently 25 pointed out. The restraining-pawls 80 are pivoted to a stationary portion of the frame of the machine and being held normally in engagement with the driving-gear by the small flat spring 81 serve to prevent any backward motion of said driving-gear.

30 Exclusive of the counter-wheels the parts as I have thus far described them are substantially the same for each bank. I shall now, however, proceed to describe the transfer devices or the means employed when the 35 cents-wheel 36 has made a complete revolution to move the dimes-wheels 37 forward a notch and when the dimes-wheel has made a revolution to move the primary wheel 38 of the dollar-wheels forward a notch. The means 40 employed to effect the transfer from the cents-wheel to the dimes-wheel and those employed to transfer from the dimes-wheel to the primary dollar-wheel are substantially identical, so that a description of one will suffice for 45 both. The counter line-shaft is formed of two independent parts 43 and 44, journaled in supports 45. The cents-wheel 36 is rigidly secured to its pinion 33 and to the cents transfer-arm 70, (shown in broken lines in Fig. 3,) 50 and all three are loose upon and turn together on the primary section 43 of the counter line-shaft, upon which and rigidly secured so as to rotate with it are the dimes-wheel 37, its pinion 34, and dimes ratchet-wheel 46. The dimes 55 transfer-arm 71 is also fixed rigidly to the primary section 43 of the counter line-shaft and upon the extreme left-hand end thereof. All of the dollar-wheels except the primary wheel 38 are mounted to turn loosely upon 60 the second section 44 of the counter line-shaft. The primary dollar-wheel 38, however, is secured rigidly thereon and, together

with the dollar-pinion 35 and the dollar ratchet-wheel 47, turns with the section 44 of the counter line-shaft. The other dollar counter-wheels 39, 40, 41, and 42 are, however, loose upon the second section 44 of the counter line-shaft. The transfer from one wheel to another is effected and controlled by means of the transfer-gears 48 and locking-disks 49, which it is unnecessary to describe particularly, as they are well known in the art, being clearly shown and described in the patent to Thomas Carney, No. 532,762, dated January 22, 1895.

The vertical transfer-pawl arm 50 is pivoted near its lower end to the vertically-extending bracket 51, and to its upper end is pivoted the transfer-pawl 52, which engages its transfer ratchet-wheel 46, being held in engagement therewith by the spring 53. The rigid locking member 54 of the transfer-pawl arm when in its normal position, as shown in Fig. 3, is arranged to engage the transfer ratchet-wheel to lock the same from any backward movement. The upwardly-projecting transfer-hook 55 is fixed to the locking member 54 and is so positioned with reference to the cents transfer-arm 70 that when the cents-wheel is about ready to transfer, and preferably while it is moving from the "9" notch to the "0" notch, the said transfer-arm 70 will engage with and force the said transfer-hook forward out of its path, thereby drawing the transfer-pawl arm forward, whereupon the transfer-pawl being thrown forward will engage the next higher notch of the transfer ratchet-wheel and upon the transfer-pawl arm being returned to normal position will turn the dimes-wheel one notch. The transfer-pawl arm is returned to normal position by means of the cam-wheel 56, which is journaled upon the horizontal shaft 22 and which co-operates with the lug or projection 57 upon the transfer-pawl arm, whereby when the cam-wheel is at rest in normal position the transfer-pawl may be forced forward and the projection 57 will fit into one of the notches of the cam-wheel; but upon the succeeding operation of any key, by which the cam-wheel will be turned a notch, the transfer-pawl arm will be forced back and the proper transfer effected. To turn the cam-wheels at every operation of a key, I employ a universal bar or keyboard 58, which extends entirely across the keys and is pivoted in the side frames 10 11 some distance above the plane of and with its swinging edge resting upon the keys. Every time a key is operated the said bar or keyboard will be moved up a certain distance and back. The standards 59 are secured rigidly to the upper surface of the said keyboard, and each in its upper end has a spring-pressed plunger 60, having a beveled face 61, by means of which when the bar is moved upward on striking the cam-wheel, which is held from backward movement by the retaining-spring 62, the plunger will be pushed down into the

standard to permit the latter to pass by the cam-wheel. On the return or downward stroke, however, the plunger will engage one of the teeth of the cam-wheel and turn it a notch, the universal keyboard and the standard carried by it then returning to normal position.

As before stated, the transfer devices just enumerated have been described as operating to effect the transfer from the cents counter-wheel to the tens or dimes wheel; but, as will be seen, substantially identical means may be and are employed to transfer from the tens or dimes wheel to the hundreds or dollar wheels.

The movement transmitted to one of the swinging registering-boards is proportionate to the numerical value of the operated key by reason of the fact that the key-cams are graduated—that is, their operating-surfaces 73 are variously inclined, so as to move the swinging registering-boards according to the numerical value of the respective keys. Thus, for example, the cam on the nine-cent key will swing the cents-board and consequently turn the driving-gear 22 nine times as far as will the one-cent cam. The same may be said of the keys in all the banks when the numerical values of the keys in the tens or dimes banks represent even multiples of five cents only. Where, however, as in my present machine, a set of eighteen keys representing the multiples, both odd and even, from ten cents to ninety-five cents, are employed in the tens or dimes bank, it is difficult to adjust the parts actuating the registering-board which coöperates with this set of keys with sufficient nicety to insure absolute accuracy in registering. In the tens bank, therefore, instead of having a different degree of inclination to the operating-surface of each of the eighteen key-cams I arrange them in nine pairs, the two comprising each pair being duplicates of each other. Nine of these cams, comprising one from each of the pairs referred to, are actuated by the keys representing the even multiples of five. The other nine cams are actuated by the keys representing odd multiples of five cents, but in each case register five less than the numerical value of the operated key. Therefore to bring the registration up to the true amount I provide means, which I shall presently describe, whereby when any key representing an odd multiple of five is operated the five-cent-key cam shall be actuated automatically and simultaneously with that of the operated key and whereby each key representing an odd multiple of five registers its true amount. To this end I provide an auxiliary keyboard 63, which is journaled upon the horizontal shaft 64 beneath the key-levers and which comprises a series of ten prongs—that is, as many prongs as there are keys representing odd multiples of five cents. Each of such keys, except the five-cent key, is provided near its rear end with a pin or stud 65, upon which respectively the

ends of the prongs of the auxiliary keyboard rest, by means of which when the five-cent key is pressed the said keyboard 63 will not be moved, but when any other key representing an odd multiple of five cents is operated the auxiliary keyboard will be moved up and back a determined distance for a purpose to be presently described. The five-cent key is different from all the others in that the cam is not secured directly to the key-lever, but is mounted side by side with it on the five-cent-key cam-lever 66, which is, like the key-levers, pivoted upon the horizontal shaft 12, as is particularly shown in Figs. 5 and 6 of the drawings. The said lever 66 is also slotted on an arc described from the axis of the shaft 12 as a center, and a headed pin 67, passing through the slot into the key-lever 6, operates to limit the movement that the five-cent-key cam can make independently of the five-cent key 65^a. Moreover, at its swinging end the five-cent-key cam-lever 66 is provided with a projection or shoulder 68, which extends across over both the five-cent-key lever 65^a and the five-cent tine or prong 64 of the five-cent keyboard 63, whereby the operation of the five-cent key will actuate the five-cent-key cam to register its value on the counter. By virtue of this construction also when any key representing an odd multiple of five is operated it will operate the five-cent-key cam for the purpose above described.

In devices similar to mine much trouble has been encountered through a tendency of the adding devices to overthrow when a key is operated with more than ordinary violence. To prevent the possibility of overthrow in my machine, I provide means to automatically lock the adding devices as soon as the operated key has completed its stroke. To this end I secure to the universal keyboard 58 three stops 75, 76, and 77—that is, as many as there are counter-driving gears. These stops are so positioned that the instant an operated key has completed its stroke the stops will engage the teeth of the counter-driving gears and, depriving the parts of their momentum, instantly bring the adding devices to a full stop, so that no overthrow is possible. The parts remain thus locked for an instant only, when the universal keyboard falls back to normal position, thereby withdrawing the stops from engagement with the counter-driving gears and leaving the machine in condition to be again operated.

It would of course be highly important in my machine as thus described to have a key-arrester to compel the full and complete operation of any key that may be started, and any of the well-known forms of key-arresters may be employed for this purpose—for instance, that shown in the patent of F. J. Patterson, No. 437,236, dated September 30, 1890.

The operation of my machine is as follows: Suppose, for example, the eight-cent key pressed. The eight-cent-key cam 72 will be raised and its operating-surface 73 will con-

tact with the cents registering-board. As the cam advances it forces the registering-board to swing on its shaft 22, thus actuating the pawl-arm and through it the driving-gear and 5 finally the counter. If some key representing an odd multiple of five be operated—for example, the thirty-five-cent key—the five-cent cam will be simultaneously operated through the medium of the five-cent key- 10 board. The thirty-five-cent-key cam will register thirty on the counter and the five-cent cam will add five, in this manner bringing the registration up to its true amount.

In my present invention as thus far described the special keys, by which I mean the "charge" key, the "received-on-account" key, the "paid-out" key, and the "no-sale" key, (shown in Fig. 1,) have no key-cams, their function when they are operated being simply 15 to release the cash-drawer (where one is used) and to display appropriately-worded tablets or indicators.

An independent feature of my invention consists of the detail-adding devices, in combination with the totalizing-counter, by means of which not only is a record made on the totalizing-counter of the total cash sales, but the detail-adding wheels, one pair of which coöperates with each key, show how many 20 sales have been made and the amount that has been registered on each key. By reference to Fig. 8 it will be seen that the primary detail-adding wheel 102 and its secondary detail-adding wheel 103 are mounted upon trans- 25 verse shafts 100 and 101, respectively. The primary wheel 102 is provided with a toothed periphery 102' along one edge, in which the pawl 97 engages, as shown. The said pawl is pivoted to the key, and a coiled spring 99, 30 connected at its ends to the key and to the pawl, keeps the pawl normally in engagement with the toothed periphery. It will readily be seen that whenever the key is pressed the primary adding-wheel will be turned a notch. 35 Projecting from the periphery, which bears the adding-numbers, is a pin or stud 104, which is arranged so that when the primary detail-adding wheel has completed a revolution the said pin or stud will engage the 40 toothed portion 103' of the secondary detail-adding wheel 103 and turn it a notch, whereupon the primary wheel returns to zero position, all in a manner now well known in the art. The retaining-pawls 106 and 107 are 45 mounted upon the transverse shaft 105 and are held in engagement with the respective detail-adding wheels by the spring 108, as will be readily understood. As before stated, each key is provided with a pair of these 50 tail-wheels, from which it will be seen that at the close of a day's business or whenever it may be desired to take off the record from the register the totalizing-counter will show the total cash sales and the detail-wheels will 55 show the amounts that have been registered on the respective keys. Of course the sum- 60 total amounts shown on the detail-wheels

operated by the cash-keys will balance the amount shown on the totalizing-counter. The so-called "special" keys—that is, the "charge," "received-on-account," "paid-out," and "no-sale" keys—each operate a pair of the detail-wheels, which wheels thus show the number of transactions that have been recorded on the special key, respectively. 75

Having thus fully described my invention, I claim as new and desire to secure by Letters Patent of the United States—

1. In a cash-register, the combination with 80 a series of keys, of a series of graduated cam-edged projections on said keys, a swinging registering-board arranged to be engaged by said cam edges and thus swung to a greater or less extent according to the inclination of 85 said edges, a counter and means for transmitting the movements of the registering-board to said counter.

2. In a cash-register, the combination with 90 a series of keys, of a series of graduated cam-edged projections on said keys, a swinging registering-board arranged to be engaged by said cam edges and thus swung to a greater or less extent according to the inclination of 95 said edges, a pawl carried by said registering-board, a gear engaged by said pawl, and a counter arranged to be operated by said gear.

3. In a cash-register, the combination with 100 a series of keys arranged to operate a series of key-cams, of a counter, intermediate mechanism arranged to transmit the value of an operated key from its key-cam to the counter, a bar common to and actuated by the keys, and stops carried by said common bar and arranged to be thrown into engagement with 105 said intermediate mechanism to lock the counter upon the completion of the stroke of any operated key.

4. In a cash-register the combination with 110 a series of keys bearing graduated key-cams arranged to coöperate with a swinging board, of a counter, a gear-wheel arranged to transmit movement from said board to the counter, a bar common to and actuated by the keys, and a stop carried by said common bar and 115 arranged to be thrown into engagement with said gear-wheel to lock the counter upon the completion of the stroke of any operated key.

5. In a cash-register of the class described, a counter comprising devices to effect the 120 transfer from counter-wheels of lower denomination to a counter-wheel of higher denomination, consisting of a transfer-pawl, a cam-wheel to move said pawl in one direction, means for moving said pawl in an opposite 125 direction, a bar common to all the keys and a spring-pressed plunger carried by the said bar and arranged to turn the cam-wheel a notch at each operation of a key.

6. In a cash-register, the combination with 130 the pivoted transfer-pawl arm bearing the transfer-pawl and the transfer-hook also carried by the transfer-pawl arm, of the counter, means arranged to engage the transfer-hook

to move the transfer-pawl into engagement with one of the counter-wheels, and independent means for returning the transfer-pawl to normal position to complete the transfer.

key cam pivoted independently of the five-cent key and having a slot-and-pin connection with the latter, and a shoulder secured upon said key-cam and operatively connecting the same with both the five-cent key and the supplemental keyboard. 25

9. In a cash-register of the class described, a series of keys a counter comprising devices to effect the transfer from counter-wheels of 30 lower denominations to counter-wheels of higher denominations, consisting of a transfer-pawl, operating means for said pawl and an arm carrying a spring-pressed plunger for engagement with the operating means and 35 arranged to be operated by any one of the keys.

ALLEN I. BLANCHARD.

Witnesses:

EDWARD RECTOR,
LEONORA WISEMAN.

5 7. In a cash-register having a five-cent key and other keys representing the odd multiples of five cents, the combination with the counter and registering-board, of the key-cams fixed to and carried by the keys, the supplemental keyboard having tines connecting with each of the before-mentioned keys except the five-cent key, a five-cent-key cam pivoted independently of the five-cent key, and having a shoulder extending across both the five-cent key and the supplemental key-coupler, for the purpose described. 15

8. In a cash-register of the class described, the combination with the counter and the registering-board of the key-cams carried by 20 the keys, the supplemental keyboard having tines connecting with the keys, a five-cent-
